United States Patent

Des. 237,192
Patented Oct. 14, 1975

237,192

CONNECTOR COVER

Ikuzo Uesawa, Tokyo, Japan, assignor to The Furukawa
Electric Company Limited, Tokyo, Japan

Filed July 5, 1973, Ser. No. 376,384

Term of patent 14 years

Int. Cl. D13—99

U.S. Cl. D26—1 A

FIG. 1.

FIG. 2.

5

FIG. 3.

FIG. 4.

FIG. 5.

FIG. 6.

FIG. 1 is a front elevational view of a connector cover showing my new design;

FIG. 2 is a side elevation view thereof;

FIG. 3 is a top plan view thereof;

FIG. 4 is a bottom plan view thereof;

FIG. 5 is a sectional view taken along the line 5—5 of FIG. 3 in the direction indicated generally; and

FIG. 6 is a sectional view similar to FIG. 5, the wires and connector being shown in broken lines for illustrative purposes only.

The rear elevation and opposite side elevation configurations correspond to the views shown in FIGS. 1 and 3 respectively.

I claim:
The ornamental design for a connector cover, substantially as shown and described.
